GAS-BLAST ELECTRIC CIRCUIT BREAKER

Donald Foster Amer, Newcastle-on-Tyne, England, assignor to A. Reyrolle & Company Limited, Hebburn-on-Tyne, England, a company of Great Britain

Application December 6, 1946, Serial No. 714,598
In Great Britain December 18, 1945

20 Claims. (Cl. 200—148)

1

This invention relates to gas-blast electric circuit-breakers of the kind comprising two relatively movable main contacts, a nozzle or vent associated therewith and a gas delivery chamber or reservoir on the high pressure side of the nozzle so that when a gas blast orifice at the outlet of an exhaust chamber or passage on the low pressure side of the nozzle is opened, a blast of deionising gas contained in or delivered to the delivery chamber or reservoir flows through the nozzle and thus assists in extinguishing the arc initiated between the separating contacts.

A gas-blast circuit-breaker according to the present invention is provided with an exhaust orifice in tandem with the blast orifice, the circuit-breaker contacts, blast orifice, and exhaust orifice being so controlled sequentially by one and the same control device that, during opening of the circuit-breaker, the blast orifice is opened before the exhaust orifice is closed and, during closing of the circuit-breaker, the exhaust orifice is opened before the blast orifice is closed.

Preferably, the blast orifice and exhaust orifice respectively constitute the gas inlet and outlet of an expansion chamber so that, during opening of the circuit-breaker, pressure gas will flow past the contacts into the expansion chamber and the build-up of back pressure within the exhaust chamber will be delayed until after the arc has been extinguished, whereas during reclosing of the circuit-breaker free flow of pressure gas past the contacts will only occur for the brief period while both the orifices are open, the pressure within the exhaust chamber being restored substantially immediately after the blast orifice is closed, whilst the gases within the expansion chamber, from the previous opening of the circuit-breaker, are discharged to the atmosphere. It will be apparent that, with this arrangement the major part of the exhaust gas is not discharged to the atmosphere during opening of the circuit-breaker, but is held in the expansion chamber until the commencement of the next closing operation thus allowing adequate time for cooling of the gas before final discharge.

Instead of the gas flow being throttled by at least one of the relatively movable contacts lying within the nozzle, these contacts may be arranged wholly outside the nozzle, the flow of gas being throttled by the restricted cross-section available for the flow of gas through the nozzle.

The blast orifice and exhaust orifice may be controlled respectively by a blast valve and an exhaust valve, the two valves and the circuit-

2

breaker contacts being operated sequentially by the one control device.

In one arrangement, the exhaust orifice constitutes the gas discharge port of a gas-tight casing enclosing the gas delivery chamber or reservoir, the circuit-breaker contacts, exhaust chamber or passage and the means for controlling the contacts and the gas blast and exhaust orifices within the said casing. The single control device 10 may then be connected to the control means within the casing through an operating spindle extending through the exhaust orifice, the necessity for providing the control means with any gas-tight glands or other sealing joints against leakage to atmosphere, being thus wholly obviated.

Conveniently, the flow of gas through the nozzle or vent is strangled or throttled when the blast orifice opens, so as to promote a depression 20 on the exhaust side of the nozzle during separation of the contacts. To this end, the flow of gas through the nozzle may be throttled by at least one of the relatively movable contacts lying within the nozzle when the circuit-breaker is in the closed condition.

The nozzle or vent may comprise two aligned apertures formed respectively in opposite walls of an exhaust conduit in open communication with and supplementing the volume of the exhaust chamber, at least one of the relatively movable contacts extending into the nozzle when the circuit-breaker is in the closed condition. If desired two or more such nozzles may be arranged in alignment, the several nozzles being in 30 open communication with the exhaust chamber through separate exhaust conduits respectively. Whether one or a plurality of nozzles is employed, however, the arrangement is conveniently such that, during opening of the circuit-breaker, the blast orifice is opened before the nozzle or nozzles is, or are, vacated by the contact or contacts, so that the depression in the exhaust chamber is accentuated before the contacts separate 40 rate.

The invention may be carried into practice in various ways but three convenient practical arrangements, each according to the invention, are shown somewhat diagrammatically and by way 50 of example, in the accompanying drawings, in which

Figure 1 shows the circuit-breaker partly in vertical section,

Figures 2 and 3 are diagrammatic representations indicating the sequence of operations.

Figures 4 and 5 are vertical sections of two modified constructions respectively, and

Figure 6 is a purely diagrammatic illustration of a modified arrangement.

In the arrangement shown in Figure 1, as applied to a double-break circuit-breaker of the open type, the switch gear is carried on a central vertical post insulator A and comprises two external horizontal hollow insulators B¹, B² carried respectively at opposite ends of a central gas delivery chamber or reservoir B. Arranged between the central gas delivery chamber B and the upper end of the hollow supporting vertical post insulator A is an expansion chamber C provided at its lower end with a non-return outlet valve C¹ of the annular flap type. Gas under pressure is supplied continuously beside a conduit A¹ extending upwards through the vertical post insulator A, the central gas delivery chamber B being in open communication at opposite ends with two internal horizontal insulators or contact chambers B³ arranged within the horizontal external insulators B¹, B² above referred to.

Arranged within the central gas delivery chamber B and extending axially from opposite ends thereof into the two horizontal contact chambers B³ is an exhaust chamber D furnished at its two outer ends respectively with inwardly flaring nozzles D¹, each nozzle having associated therewith a plug-like contact D² carried by an axial piston D³ loaded by a spring D⁴, this plug-like contact being engaged laterally by spring-loaded fixed contact fingers D⁵. The two poles of the circuit-breaker are connected at opposite ends of the circuit-breaker to these fixed contacts D⁵ respectively.

Arranged in axial alignment with the vertical post insulator A and the cylindrical expansion chamber C thereon is a gas blast orifice or valve seating E¹ leading from the expansion chamber C into the exhaust chamber D, the lower end of the expansion chamber C having a generally similar valve seating C² constituting an exhaust orifice and leading from the expansion chamber C to the atmosphere past the non-return flap valve C¹. The gas blast orifice E¹ and the exhaust orifice C² thus constitute the inlet to and outlet from the expansion chamber C. A horizontal rotary control shaft F in the base of the vertical post insulator A is connected through a crank F¹ and a vertical insulating rod F² to the stem C³ of an exhaust valve C⁴ controlling the exhaust orifice C² of the expansion chamber C, the upper end of this exhaust valve C⁴, whose stem C³ extends axially through the exhaust orifice C², being connected through toggle mechanism C⁵, disposed within the expansion chamber C, to the lower end of the spindle E² of a blast valve E controlling the blast orifice E¹. The upper end of the blast valve spindle E² is vertically movable through a gland E³ in the wall of the exhaust chamber D and is connected to toggle mechanism E⁴ lying within the gas delivery chamber or reservoir B and operatively connected to two horizontal rod-like moving contacts G extending through glands G¹ in the exhaust chamber D and whose outer or free ends cooperate respectively with the wider ends of the two nozzles D¹.

The gas delivery chamber B (including the internal horizontal tubular insulators B³), and the expansion chamber C thus together constitute a gas-tight outer casing whose discharge port is constituted by the exhaust orifice C² so

that this casing encloses the gas delivery chamber or reservoir B, the circuit-breaker contacts G, D², exhaust chamber D and the valves C⁴ and E and toggle mechanisms C⁵ and E⁴ controlling the blast and exhaust orifices E¹, C² within the casing and the mechanism for operating the contacts G.

Assuming that the circuit-breaker is in the open position, as shown in Figures 1 and 2, the exhaust valve C⁴ at the lower end of the expansion chamber C is closed whilst the blast valve E is open and the outer or free ends of the two horizontal rod-like moving contacts G lie clear of the two cooperating nozzles D¹, the axial plug-like contacts D² on the high-pressure sides of the nozzles D¹ being then held in their innermost positions towards the nozzle by their control springs D⁴. The gas pressures within the expansion chamber C, exhaust chamber D and gas delivery chamber or reservoir B are now all substantially equal. If now the circuit-breaker is to be closed, the single horizontal control shaft F in the base of the vertical supporting post insulator A is operated so that the exhaust valve C⁴ in the base of the expansion chamber C is opened and the gas within this expansion chamber C is discharged to the atmosphere, this chamber as also the exhaust chamber D being at the same time scavenged due to the blast valve E being still in its open position. The blast valve E now closes (Figure 3) under the action of the toggle mechanism E⁴ within the expansion chamber C so that the pressure within the exhaust chamber D is again restored to that within the gas delivery chamber or reservoir B. As the blast valve E moves towards its closed position, the toggle mechanism E⁴ within the gas delivery chamber B moves the two horizontal rod-like moving contacts G outwards so that each of these contacts enters and passes through the associated nozzle D¹ until it bears against the adjacent end of the associated plug-like contact D², the circuit being thus closed through the two sets of cooperating contacts G, D² in series.

To reopen the circuit-breaker the horizontal shaft F is operated in the reverse direction thus opening the blast valve E before the exhaust valve C⁴ is closed so that, immediately prior to separation of the contacts G, D² of the circuit-breaker, that is to say while both the valves C⁴, E are open, gas flows through the exhaust chamber D and expansion chamber C to the atmosphere. The exhaust valve C⁴ now closes and the gas on the low pressure sides of the nozzles D¹ expands into the expansion chamber C, a blast of deionising gas flowing from the gas delivery chamber B through both nozzles D¹ as the cooperating contacts G, D² move apart. During this operation the gas flow through the nozzles D¹ is strangled or throttled by the cooperating horizontal rod-like contacts G, but after these have separated and the arcs have been extinguished the back pressure within the exhaust chamber D is again built up to the same value as the pressure within the gas delivery chamber B.

It will be apparent that with this arrangement a predetermined flow of deionising gas to the exhaust side of the nozzles D¹ takes place at each opening operation so that the quantity of gas employed is automatically controlled whilst the back pressure is built up, after separation of the contacts, at a predetermined rate. Moreover, the exhaust gases from any one opening operation are, for the most part, not discharged to the at-

mosphere during that operation but are held within the expansion chamber C and exhaust chamber D until the next closing operation, thus allowing adequate time for cooling.

In the modified construction shown in Figure 4 and also according to the invention but as applied to metal-clad switchgear, the expansion chamber H and exhaust chamber J are arranged wholly within the outer casing constituting the gas delivery chamber or reservoir L. The exhaust chamber J, communicating with the expansion chamber H past a blast valve J¹ as described above, has an extension or conduit J² lying laterally between a fixed plug-like contact K¹ and a longitudinally movable rod-like moving contact K. The opposite walls of the conduit J² are furnished respectively with two vents or nozzles J³, J⁴ lying in axial alignment with each other and with the two cooperating contacts K, K¹. The two poles of the circuit-breaker, for example carried by bushing insulators M, M¹ of the plug-in type, extend through the wall of the gas delivery chamber or reservoir L to the cooperating contacts K, K¹ respectively, the fixed plug-like contact K¹ being conveniently electrically connected to the lateral conduit J² of the exhaust chamber J through a limiting resistance M².

With this arrangement, when the circuit-breaker is open as shown in Figure 4, the exhaust valve H¹ in the expansion chamber H is closed whilst the blast valve J¹ between the expansion chamber H and the exhaust chamber J is open, the gas delivery chamber or reservoir L being then in open communication through the vents or nozzles J³, J⁴ with the interior of the exhaust chamber J and expansion chamber H. When the control shaft F is operated to close the circuit-breaker the exhaust valve H¹ is opened so that the gas within the chamber H is discharged to the atmosphere whereupon the rod-like contact K enters the aligned vents or nozzles J³, J⁴ and the blast valve J¹ closes, the rod-like moving contact K then passing through the two aligned vents or nozzles J³, J⁴ and into engagement with the cooperating fixed plug-like contact K¹. As with the construction first described, when the circuit-breaker is opened, the blast valve J¹ is opened before the exhaust valve H¹ is closed, whereupon the gas within the exhaust chamber J expands into the expansion chamber H, the presence of the moving contact rod K within the nozzles or vents J³, J⁴ throttling the flow of gas from the gas delivery chamber L into the exhaust chamber J. As the moving contact K is withdrawn from the nozzles or vents J³, J⁴ a blast of deionising gas flows through the nozzles from the gas delivery chamber L until the pressure within the exhaust chamber J and expansion chamber H are again restored to that within the gas delivery chamber L.

In the construction shown in Figure 5, which shows the invention as applied to a circuit-breaker of the open type, the expansion chamber N is again mounted on a vertical hollow post insulator O as described with reference to the first arrangement, the expansion chamber N and the gas delivery chamber P being arranged one above the other upon the vertical post insulator O. Arranged at the upper end of the gas delivery chamber P is a further hollow insulating chamber Q carrying the fixed contact Q¹ at its upper end with the interior of this insulating casing Q in open communication with the gas delivery chamber P. The vertical moving contact rod R is actuated from the stem S¹ of the blast valve S through

toggle mechanism S² disposed wholly within the gas delivery chamber or reservoir P, the upper end of the moving contact rod R cooperating with the vents or nozzles R¹ arranged in opposite walls of a plurality of lateral conduits R² in open communication with, and supplementing the volume of, the exhaust chamber T. The operation of this construction is similar to that described with reference to Figure 4 except that the moving contact rod R, instead of cooperating with a single pair of vents or nozzles of one lateral exhaust conduit, cooperates with a plurality of aligned pairs of such nozzles R¹, each pair being formed in opposite walls of a separate exhaust conduit R².

In the modified construction shown in Figure 6, the circuit-breaker contacts V, V¹ cooperate wholly outside the nozzle W so that the flow of gas is throttled by the restricted cross-section available for the flow of gas through the nozzle W when the blast valve X opens, thereby promoting a depression in the extension Y¹ of the exhaust chamber Y during initial separation of the contacts V, V¹. As in Figures 4 and 5, the contact V, blast valve X and exhaust valve Y² are operated through toggle mechanism X¹ and Y³ from a single control rod Z.

Though in each of the above constructions the flow of gas from the gas delivery chamber or reservoir to the exhaust chamber is restricted by at least one contact extending into the nozzle, this arrangement may be modified by arranging the contacts wholly outside the nozzle and within the delivery chamber, the throttling of the gas flow from the delivery chamber to the exhaust chamber being then produced solely by the restricted cross-section afforded to such flow by the open nozzle.

It will be understood that the constructions described above are given by way of example only and that details may be modified to suit requirements.

For example, the gas delivery chamber or reservoir may either be maintained filled with gas under pressure or the gas may be delivered to the said reservoir or chamber only when the circuit-breaker is to be opened. For example, as shown in Figure 6 an inlet control valve Z¹ may be provided which is opened (e. g. automatically under fault conditions) by an auxiliary cam Z² on the single control shaft before this operates the blast valve X and exhaust valve Y².

What I claim as my invention and desire to secure by Letters Patent is:

1. A gas-blast electric circuit-breaker comprising a pressure-gas reservoir communicating with a gas delivery vent, two relatively movable main contacts cooperating at said vent, an exhaust chamber on the outlet side of the vent, said exhaust chamber having an outlet or blast orifice therein, a blast valve controlling the blast orifice, opening of the blast valve thus causing a blast of deionising gas to flow from the reservoir and through the vent into the exhaust chamber, thereby assisting to extinguish an arc initiated between the main contacts, a passage communicating with said exhaust chamber through the blast orifice and having an outlet or exhaust orifice therein, an exhaust valve controlling said exhaust orifice, the blast valve and exhaust valve being thus disposed in tandem, and a single control device whereby the main contacts, blast valve and exhaust valve are sequentially controlled, operation of said control device to open the contacts causing the blast valve to be opened before

the exhaust valve is closed, whereas operation of said device to close the contacts causes the exhaust valve to be opened before the blast valve is closed.

2. A gas-blast electric circuit-breaker comprising a pressure gas reservoir communicating with a gas delivery vent, two relatively movable main contacts cooperating at said vent, an exhaust chamber on the outlet side of the vent, said exhaust chamber having an outlet or blast orifice therein, a blast valve controlling said blast orifice, opening of said blast valve thus causing a blast of deionising gas to flow from the reservoir and through the vent into the exhaust chamber thereby assisting to extinguish an arc initiated between the main contacts, an expansion chamber communicating with said exhaust chamber through the blast orifice and having an outlet or exhaust orifice therein, an exhaust valve controlling said exhaust orifice, the blast valve and exhaust valve being thus disposed in tandem, and a single control device whereby the main contacts, blast valve and exhaust valve are sequentially controlled, operation of the said control device to open the contacts causing the blast valve to be opened before the exhaust valve is closed so that pressure gas flows through the vent past the separating contacts, and through the exhaust chamber and expansion chamber to the atmosphere, the build-up of back pressure within the exhaust chamber being delayed until after the arc has been extinguished, whereas operation of the said control device to close the contacts causes the exhaust valve to be opened before the blast valve is closed so that free flow of pressure gas past the contacts will only occur for the brief period while both valves are open, the pressure within the exhaust chamber being restored when the blast valve has closed, whilst the gases within the expansion chamber, from the previous opening of the circuit-breaker, are discharged to the atmosphere past the open exhaust valve.

3. A gas-blast electric circuit-breaker comprising a pressure-gas reservoir communicating with a gas delivery nozzle, two relatively movable main contacts cooperating at said nozzle, an exhaust chamber on the outlet side of the nozzle, said exhaust chamber having an outlet or blast orifice therein, a blast valve controlling said blast orifice, opening of said blast valve thus causing a blast of deionising gas to flow from the reservoir and through the nozzle into the exhaust chamber thereby assisting to extinguish an arc initiated between the main contacts, an expansion chamber communicating with said exhaust chamber through the blast orifice and having an outlet or exhaust orifice therein, an exhaust valve controlling said exhaust orifice, the blast valve and exhaust valve being thus disposed in tandem, and a single control device whereby the main contacts, blast valve and exhaust valve are sequentially controlled, operation of the said control device to open the contacts causing the blast valve to be opened before the exhaust valve is closed so that pressure gas flows through the nozzle past the separating contacts, and through the exhaust chamber and expansion chamber to the atmosphere, the build-up of back pressure within the exhaust chamber being delayed until after the arc has been extinguished, whereas operation of the said control device to close the contacts causes the exhaust valve to be opened before the blast valve is closed so that free flow of pressure gas past the contacts will only occur for the brief period while both valves are open, the pressure

within the exhaust chamber being restored when the blast valve has closed, whilst the gases within the expansion chamber, from the previous opening of the circuit-breaker, are discharged to the atmosphere past the open exhaust valve.

4. A gas-blast circuit-breaker as claimed in claim 1, in which the exhaust orifice constitutes the gas discharge port of a gas-tight casing enclosing the reservoir, circuit-breaker contacts, exhaust chamber and the means for controlling the contacts and the gas blast and exhaust orifices.

5. A gas-blast electric circuit-breaker comprising a pressure gas reservoir communicating with a gas delivery vent, two relatively movable main contacts cooperating at said vent, an exhaust chamber on the outlet side of the vent, said exhaust chamber having an outlet or blast orifice therein, a blast valve controlling said blast orifice, opening of said blast valve thus causing a blast of deionising gas to flow from the reservoir and through the vent into the exhaust chamber thereby assisting to extinguish an arc initiated between the main contacts, an expansion chamber communicating with said exhaust chamber through the blast orifice and having an outlet or exhaust orifice therein, an exhaust valve controlling said exhaust orifice, the blast valve and exhaust valve being thus disposed in tandem, a gas-tight casing enclosing the reservoir, circuit-breaker contacts, exhaust chamber, blast valve and exhaust valve, said exhaust orifice constituting the gas discharge port of the gas-tight enclosing casing, and a single control device whereby the main contacts, blast valve and exhaust valve are sequentially controlled within the casing, operation of the said control device to open the contacts causing the blast valve to be opened before the exhaust valve is closed so that pressure gas flows through the vent past the separating contacts, and through the exhaust chamber and expansion chamber to the atmosphere, the build-up of back pressure within the exhaust chamber being delayed until after the arc has been extinguished, whereas operation

45 of the said control device to close the contacts causes the exhaust valve to be opened before the blast valve is closed so that free flow of pressure gas past the contacts will only occur for the brief period while both valves are open, the pressure within the exhaust chamber being restored when the blast valve has closed, whilst the gases within the expansion chamber, from the previous opening of the circuit-breaker, are discharged to the atmosphere past the open exhaust valve.

6. A gas-blast electric circuit-breaker as claimed in claim 5, in which the single control device is connected to the control means within the casing through an operating spindle extending through the exhaust orifice.

7. A gas-blast electric circuit-breaker comprising a pressure-gas reservoir communicating with a gas delivery vent, two relatively movable main contacts cooperating at said vent, an exhaust chamber on the outlet side of the vent, said exhaust chamber having an outlet or blast orifice therein, a blast valve controlling the blast orifice, opening of the blast valve thus causing a blast of deionising gas to flow from the reservoir and through the vent into the exhaust chamber thereby assisting to extinguish an arc initiated between the main contacts, a passage communicating with said exhaust chamber through the blast orifice and having an outlet or exhaust orifice therein, an exhaust valve controlling said

exhaust orifice, the blast valve and exhaust valve being thus disposed in tandem, a gas-tight casing enclosing the reservoir, circuit-breaker contacts, exhaust chamber passage, blast valve, and exhaust valve, said exhaust orifice constituting the gas discharge port of the gas-tight enclosing casing, and a single control device whereby the main contacts, blast valve and exhaust valve are sequentially controlled, operation of said control device to open the contacts causing the blast valve to be opened before the exhaust valve is closed, whereas operation of said device to close the contacts causes the exhaust valve to be opened before the blast valve is closed.

8. A gas-blast electric circuit-breaker as claimed in claim 7, in which the single control device is connected to the control means within the casing through an operating spindle extending through the exhaust orifice.

9. A gas-blast circuit-breaker as claimed in claim 1, having means whereby the flow of gas through the vent is throttled when the blast orifice opens, a depression on the exhaust side of the vent being thus promoted during separation of the contacts.

10. A gas-blast circuit-breaker as claimed in claim 5, having means whereby the flow of gas through the vent is throttled when the blast orifice opens, a depression on the exhaust side of the vent being thus promoted during separation of the contacts.

11. A gas-blast electric circuit-breaker comprising a pressure-gas reservoir, an exhaust chamber, an exhaust conduit in open communication with and supplementing the volume of the exhaust chamber which has an outlet or blast orifice therein, the exhaust conduit having two aligned apertures formed respectively in opposite walls of the exhaust conduit and together constituting a vent through which the reservoir communicates with the exhaust conduit, two relatively movable main circuit-breaker contacts at least one of which extends into the vent when the circuit-breaker contacts are closed, a blast valve controlling said blast orifice, opening of the blast valve thus causing a blast of deionising gas to flow from the reservoir and through the vent, as throttled by the said contact therein, into the exhaust conduit and exhaust chamber thereby assisting to extinguish an arc initiated between the main contacts, a passage communicating with said exhaust chamber through the blast orifice and having an outlet or exhaust orifice therein, an exhaust valve controlling said exhaust orifice, the blast valve and exhaust valve being thus disposed in tandem, and a single control device whereby the main contacts, blast valve and exhaust valve are sequentially controlled, operation of said control device to open the contacts causing the blast valve to be opened before the exhaust valve is closed, whereas operation of said device to close the contacts causes the exhaust valve to be opened before the blast valve is closed.

12. A gas-blast electric circuit-breaker comprising a pressure-gas reservoir, an exhaust chamber, an exhaust conduit in open communication with and supplementing the volume of the exhaust chamber which has an outlet or blast orifice therein, the exhaust conduit having two aligned apertures formed respectively in opposite walls of the exhaust conduit and together constituting a vent through which the reservoir communicates with the exhaust conduit, two relatively movable main circuit-breaker contacts at least one of which extends into the vent when

the circuit-breaker contacts are closed, a blast valve controlling said blast orifice, opening of the blast valve thus causing a blast of deionising gas to flow from the reservoir and through the vent,

- 5 as throttled by the said contact therein, into the exhaust conduit and exhaust chamber thereby assisting to extinguish an arc initiated between the main contacts, an expansion chamber communicating with said exhaust chamber through the blast orifice and having an outlet or exhaust orifice therein, an exhaust valve controlling said exhaust orifice, the blast valve and exhaust valve being thus disposed in tandem, and a single control device whereby the main contacts, blast valve
- 10 and exhaust valve are sequentially controlled, operation of the said control device to open the contacts causing the blast valve to be opened before the exhaust valve is closed so that pressure gas flows through the vent past the separating contacts, and through the exhaust chamber and expansion chamber to the atmosphere, the build-up of back pressure within the exhaust chamber being delayed until after the arc has been extinguished, whereas operation of the said control
- 15 device to close the contacts causes the exhaust valve to be opened before the blast valve is closed so that free flow of pressure gas past the contacts will only occur for the brief period while both valves are open, the pressure within the exhaust
- 20 chamber being restored when the blast valve has closed, whilst the gases within the expansion chamber, from the previous opening of the circuit-breaker, are discharged to the atmosphere past the open exhaust valve.

- 25 13. A gas-blast electric circuit-breaker as claimed in claim 11, in which the exhaust orifice constitutes the gas discharge port of a gas-tight casing enclosing the reservoir, circuit-breaker contacts, exhaust chamber and the means for
- 30 40 controlling the contacts and the gas blast and exhaust orifices.

- 35 14. A gas-blast circuit-breaker as claimed in claim 12, having a gas-tight casing enclosing the reservoir, circuit-breaker contacts, exhaust conduit, exhaust chamber, blast valve and exhaust valve, said exhaust orifice constituting the gas discharge port of the gas-tight enclosing casing.

- 40 15. A gas-blast electric circuit-breaker comprising a pressure-gas reservoir, an exhaust chamber, an exhaust conduit in open communication with and supplementing the volume of the exhaust chamber which has an outlet or blast orifice therein, the exhaust conduit having two aligned apertures formed respectively in opposite walls of the exhaust conduit and together constituting a nozzle through which the reservoir communicates with the exhaust conduit, two relatively movable main circuit-breaker contacts at least one of which extends into the nozzle when
- 45 60 the circuit-breaker contacts are closed, a blast valve controlling said blast orifice, opening of the blast valve thus causing a blast of deionising gas to flow from the reservoir and through the nozzle, as throttled by the said contact therein, into the exhaust conduit and exhaust chamber thereby assisting to extinguish an arc initiated between the main contacts, an expansion chamber communicating with said exhaust chamber through the blast orifice and having an outlet or exhaust
- 50 65 orifice therein, an exhaust valve controlling said exhaust orifice, the blast valve and exhaust valve being thus disposed in tandem, a gas-tight casing enclosing the reservoir, circuit-breaker contacts, exhaust chamber, expansion chamber, blast valve
- 55 70 and exhaust valve, said exhaust orifice constitut-

11

ing the gas discharge port of the gas-tight enclosing casing, and a single control device whereby the main contacts, blast valve and exhaust valve are sequentially controlled within the casing, operation of the said control device to open the contacts causing the blast valve to be opened before the exhaust valve is closed so that pressure gas flows through the nozzle past the separating contacts, and through the exhaust chamber and expansion chamber to the atmosphere, the build-up of back pressure within the exhaust chamber being delayed until after the arc has been extinguished, whereas operation of the said control device to close the contacts causes the exhaust valve to be opened before the blast valve is closed so that free flow of pressure gas past the contacts will only occur for the brief period while both valves are open, the pressure within the exhaust chamber being restored when the blast valve has closed, whilst the gases within the expansion chamber, from the previous opening of the circuit-breaker, are discharged to the atmosphere past the open exhaust valve.

16. A gas-blast circuit-breaker as claimed in claim 11, having at least two aligned vents, the several vents being in open communication with the exhaust chamber through separate exhaust conduits respectively.

17. A gas-blast circuit-breaker as claimed in claim 12, having at least two aligned vents, the several vents being in open communication with the exhaust chamber through separate exhaust conduits respectively.

12

18. A gas-blast circuit-breaker as claimed in claim 15, having at least two aligned nozzles, the several nozzles being in open communication with the exhaust chamber through separate exhaust conduits respectively.

19. A gas-blast circuit-breaker as claimed in claim 1, in which at least one of the main contacts, when in its closed position, extends into the associated vent so as to throttle the gas flow therethrough, operation of the control device to open the contacts, causing the blast orifice to be opened before the vent is vacated by said contact, the depression in the exhaust chamber being thus accentuated before the contacts separate.

20. A gas-blast circuit-breaker as claimed in claim 15, in which at least one of the main contacts, when in its closed position extends into the associated nozzle so as to throttle the gas flow therethrough, operation of the control device to open the contacts causing the blast orifice to be opened before the nozzle is vacated by said contact, the depression in the exhaust chamber being thus accentuated before the contacts separate.
